UNITED STATES PATENT OFFICE.

ROBERT E. CARLTON AND STUART Y. CULLEY, OF COVINGTON, KENTUCKY.

OILING ATTACHMENT FOR STREET-SPRINKLERS.

1,032,879.

Specification of Letters Patent. Patented July 16, 1912.

Application filed May 16, 1911. Serial No. 627,405.

To all whom it may concern:

Be it known that we, ROBERT E. CARLTON and STUART Y. CULLEY, citizens of the United States, and residents of Covington, 5 in the county of Kenton and State of Kentucky, have made certain Improvements in Oiling Attachments for Street-Sprinklers, of which the following is a specification.

This invention is an improvement in the 10 application of oil to the surfaces of streets or roadways, which is desirable as is well known for the laying of dust as well as for the hardening of the road; and the invention consists in certain novel constructions 15 and combinations of parts as will be hereinafter described and claimed.

In the drawing Figure 1 is a vertical section of an apparatus embodying our invention. Fig. 2 is a bottom plan view of the 20 connection, and Fig. 3 is a cross section on about line 3—3 of Fig. 2.

In carrying out the invention we employ a suitable oil holder A which may be a tank as shown in Fig. 1 and has a suitable sight 25 plate A' by which the operator can readily determine the height of oil in the tank. The tank has an opening provided with a threaded bushing B into which screws the nipple C' on the connection C, suitable 30 packing being employed at B' and the nipple C' communicating with the main tube C² midway between the ends of the latter. This main tube of the connection C² has suitable threaded or coupling portions C³ 35 and C⁴ at its ends so it can conveniently be coupled up with an ordinary garden hose or with the supply pipe of a water wagon or car which latter may be of ordinary construction.

The nipple C' has longitudinal ports 1 and 2, the former being toward the inlet end of the connection and the latter toward the discharge end and at their juncture with the main channel 3, the passages 1 and 2 40 are separated by a projecting bridge or abutment 4 which extends slightly into the main channel or passage 3 and operates to deflect or divert a portion of the water passing through the channel 3 down through the 45 passage 1 into the tank, the said passage being prolonged by a pipe 5 to a point near the bottom of the tank so that the portion of water diverted from the main tube connection will pass under the body of the oil 50 in the tank and tend to lift the same and discharge it through the passage 2 into the

main channel 3 on the opposite side of the passage 1 so that the portion of oil so discharged from the tank will mix with the water passing to a discharge nozzle and be distributed with such water on the surface 60 of the street or road so that the water will serve to allay the dust and the oil can operate immediately for its desired purpose.

A suitable valve is provided controlling 65 the oil discharge passage 2 so as to regulate the amount of oil permitted to flow to the supply pipe. This valve is shown at 6 as a plate pivoted at 7 so it can be turned to wholly or partially cut off the oil discharge passage.

In operation it will be noticed that the 70 passage for permitting the flow of water to the tank co-operates with the valved oil discharge passage from the tank and with the main tube of the connection in permitting a portion of the water supplied to the connection to be diverted for the purpose of forcing a corresponding quantity of oil 75 into the water as it passes to a discharge nozzle.

By the invention as described it will be noticed the oil is supplied at the same time the surface is sprinkled with water and is forced into the body of the stream of water 80 so it flows on with the supply stream to the discharge point.

It will be noticed that the ports 1 and 2 85 extend longitudinally of the nipple C' and parallel with each other and with the axis 90 of said nipple, this being important in securing a compact arrangement of the parts, and it will further be noticed that the bridge 4 which is integral with the nipple C' projects into and substantially constricts 95 the bore of the connection C and operates to positively deflect a portion of the material supplied at C⁴ down through the port 1 into the holder A.

We claim:

The combination in a sprinkler, of a tank, a connection having a main tube and a nipple depending therefrom and screwing into the tank, said nipple having two ports extended longitudinally through it parallel 105 with each other and with the axis of the nipple, a discharge pipe connected with the nipple and depending therefrom into the tank and communicating at its upper end with one of the nipple ports, a valve at the 110 lower end of and controlling the other one of said ports of the nipple whereby the said

100

105

110

valve will be inclosed within the tank when the latter is applied to the nipple but will be exposed for manipulation when the tank and nipple are detached, the said nipple having an integral projecting bridge extending partially across and substantially constricting the bore of the main tube and projecting from the nipple beyond the inner end of and in proximity to the port connected with the depending tube whereby to

positively deflect material supplied to the main tube through the said port and the depending tube, substantially as and for the purposes set forth.

ROBERT E. CARLTON.
STUART Y. CULLEY.
